UNITED STATES PATENT OFFICE

2,497,566

MOUNT STRUCTURE FOR ELECTRIC LAMPS

Joseph E. Stone, Cleveland Heights, and John O. Geissbuhler, South Euclid, Ohio, assignors to General Electric Company, a corporation of New York

Application April 27, 1949, Serial No. 90,012

3 Claims. (Cl. 176—39)

1

This invention relates to electric incandescent lamps in general, and more particularly to a mount construction therefor.

There are many so-called rough service applications where an electric incandescent lamp is subjected to considerable vibrations, jars or impacts, for instance in locomotive headlights, automatic mining machinery, earth moving equipment, tractors and other like equipment. In such cases, it is highly important that the filament or light source of the lamp be so supported that the forces developed by the vibrations or shocks be sufficiently dissipated in order to prevent distortion of the hot filament such as is apt to result in premature breakage or failure of the filament with consequent short lamp life.

It is an object of our invention therefore to provide an electric incandescent lamp having its filament so supported as to avoid detrimental effects of lamp vibration or impacts.

Another object of our invention is to provide an electric incandescent lamp having a flexible mount structure of simple form and which will effectively withstand vibration and impacts to which the lamp may be subjected in service.

Further objects and advantages of our invention will appear from the following description of a species thereof and from the accompanying drawing.

In the drawing, Fig. 1 is a sectional view of an electric incandescent lamp according to the invention, and Fig. 2 is an enlarged perspective view of the mount structure thereof.

In accordance with the invention, the filament-supporting end or section of an electric incandescent lamp mount is rendered flexible in all directions by making the lead-in wires or inleads of springy material and forming them, inwardly of the lamp envelope, with laterally extending and approximately opposed arcuate intermediate portions, of more or less semicircular shape, which act as a cushion between the upper filament-supporting end of the mount and the lower anchored end of the mount to absorb any shocks or vibrations to which the lamp may be subjected in service.

Referring to the drawing, the invention is there shown as applied to an electric incandescent lamp of the sealed beam type disclosed in U. S. Patent 2,148,314, D. K. Wright, and comprising a sealed glass envelope or bulb 1 consisting of preformed pressed glass reflector and cover glass sections 2 and 3, respectively, sealed together at their peripheries by fusion, as indicated at 4. The inner surface 5 of the reflector section 2 is formed either of paraboloidal shape as shown, or of any other desired optical shape, and is provided with a reflecting coating 6 of aluminum, silver or other similar light-reflective material.

2

Mounted on the rear outer side of the reflector section 2 at the region of the apex or center thereof is a base structure 7 of the general type shown and described in U. S. Patent 2,272-512, Cotman, and comprising a pair of terminal contacts 8—8 in the form of metal straps or lugs which are suitably fastened, as by soldering for instance, to the closed nipped ends 9 of respective metal ferrules or thimbles 10—10. The contact lugs 8—8 are provided with screw terminals 11—11 for connecting current supply wires thereto. The ferrules 10—10 are formed of a suitable metal which will readily "wet" and adhere to the glass of the reflector section 2 and they are provided with skirt portions 12 which are feathered to knife edges embedded and fused in the glass of the reflector section 2 around respective openings or passageways 13 through the wall thereof. The envelope 1 is provided with an exhaust tubulation 14 communicating with the interior of the envelope through an exhaust opening 15 in the envelope wall at the apex of the reflector section 2. After exhaustion of the envelope through the tubulation 14 and, if desired, introduction of a suitable gas filling such as nitrogen or argon, the tubulation 14 is sealed or tipped-off as indicated at 16.

Mounted within the envelope 1 and supported solely from the metal ferrules 10—10 in spaced relation to the envelope walls is a lamp mount structure 17 according to the invention and comprising a pair of wire inleads 18—18 secured and anchored at their outermost ends within the nipples 9 of the ferrules, as by solder 19 as shown. The inleads 18 are made of any suitable spring material, such as molybdenum or hard nickel for instance, which will not lose its temper or springy character when heated to high temperatures such as are encountered during the operation of the lamp. From the ferrules 10—10, the inleads 18—18 extend in more or less parallel spaced relation through the openings 13—13 in the wall of the reflector section 2 and into the envelope 1 where they are connected, at their innermost ends, to opposite ends of a filament 20 preferably formed of tungsten wire. In the specific case illustrated, the filament 20 is composed of two convergent coiled sections or segments joined by a bight or loop portion 21 to form a V-shaped filament approximately lying in the plane of the parallel extending portions of the inleads and mounted in the envelope 1 symmetrically about the optical axis of the reflecting surface 6 and approximately centered at the focus thereof, with the apex of the V pointing forwardly as shown and with the plane of the filament lying approximately in the reflector axis. The connection of the filament ends to the inleads 18—18 may be through small metal connecting lugs 22 suitably

fastened to the inner ends of the inleads, as by welding, and provided with U-clamps 23 within which the free ends of the filament are clamped as shown in Fig. 2. The filament 20 is additionally supported at the bight 21 thereof by an anchor or support wire 24 provided at one end with a hook 25 within which the filament bight 21 is hooked. The other end of the support wire 24 is suitably fastened in place on an insulated part of the mount structure in a manner to be hereinafter described.

In accordance with the invention the inleads 18-18, inwardly of the envelope 1, are formed with laterally bent approximately opposed arcuate or curved intermediate portions 26-26 which lie approximately in a common plane transverse to the generally parallel extending outer and inner co-planar portions 27 and 28, respectively, of the inleads 18-18. As shown in Fig. 2, the arcuate portions 26 of the inleads are approximately in the shape of opposed semi-circles located on opposite sides of the common plane of the inleads and opening or facing toward each other and having a diameter somewhat less than the spacing of the outer portions 27-27 of the inleads, with the diametral chords of the semi-circles (i. e., the imaginary lines joining the opposite ends of the semi-circles) lying approximately in the common plane of the outer and inner parallel portions 27 and 28 of the inleads. These arcuate intermediate portions 26-26 of the inleads, being free of or spaced from the walls of the envelope and being made of a springy material, therefore impart flexibility in substantially all directions (i. e., 360° solid angle) to the filament-supporting end of the mount 17 whereby any vibrations or shocks to which the lamp may be subjected in service are effectively absorbed or cushioned by such yielding intermediate portions 26.

To maintain the points of support of the filament in fixed relation to each other at all times independent of any unitary movement thereof due to lamp vibration or shock, the inner portions 28-28 of the inleads 18-18 are rigidly tied together and held in parallel relation by suitable insulative tie means which, in the particular case shown, comprises a pair of spaced cross-bars or bridges 29 and 30 each consisting of a short length of glass rod 31 having support wires 32 embedded in and projecting from its opposite ends. The cross-bars 29, 30 are secured to the inner portions 28-28 of the inleads, at spaced points therealong, by suitably fastening the support wires 32 thereto, as by welding for instance. The intermediate support wire 24 for the filament 20 is embedded and anchored in the glass rod 31 of the innermost cross-bar 29, thus maintaining the intermediate support point for the filament in fixed relation to the end supports thereof at all times. The mount structure 17 according to the invention therefore includes as a part thereof a filament-supporting section or unit, comprising the inner portions 28-28 of the inleads, the cross-bars 29, 30 and the intermediate support wire 24, which holds the filament 20 in proper relation at all times and which is capable of moving as a unit, without relative movement between the filament and the adjacent supporting parts of the said unit, during vibration or other sudden movement of the lamp.

From the foregoing it will be evident that the

mount structure 17 comprising our invention provides a simple and effective flexible supporting arrangement for the filament whereby any vibrations, jars or impacts to which the lamp may be subjected in service are readily absorbed by the yielding arcuate intermediate portions 26-26 of the inleads which act as an elastic connection or cushion between the inner or filament-supporting section of the mount and the outer or anchored section of the mount to effectively minimize distortion of the hot filament by such lamp vibrations or shocks, thus rendering the entire lamp structure especially useful for rough service applications such as a locomotive headlight or as a lighting unit for automatic mining or earth moving equipment, tractors and other similar equipment where the lamp is ordinarily subjected to unusual shock or vibration.

What we claim as new and desire to secure by Letters Patent of the United States is:

1. An electric incandescent lamp comprising an envelope, a filament in said envelope, inleads anchored to and supported from the wall of said envelope and extending into the envelope from their wall anchorages in the same general direction and in spaced relation to the envelope wall and connected at their inner ends to said filament, and bridge means insulatively and rigidly tying the inner end portions of the inleads together, said inleads being provided intermediate their anchored ends and their said bridge means with laterally extending curved portions each approximately located in a plane transverse

35 to the inleads and spaced from the envelope wall to impart flexibility to the said inleads.

2. An electric incandescent lamp comprising an envelope, a filament in said envelope, inleads anchored to and supported from the wall of said envelope and extending into the envelope from their wall anchorages in the same general direction and in spaced relation to the envelope wall and connected at their inner ends to said filament, and bridge means insulatively and

40 rigidly tying the inner end portions of the inleads together, said inleads being provided intermediate their anchored ends and their said bridge means with laterally extending approximately located in a plane transverse to the inleads and spaced from the envelope wall to impart flexibility to the said inleads.

45 3. An electric incandescent lamp comprising an envelope, a filament in said envelope, inleads anchored to and supported from the wall of said envelope and extending into the envelope from their wall anchorages in the same general direction and in spaced relation to the envelope wall

50 and connected at their inner ends to said filament, and bridge means insulatively and rigidly tying the inner end portions of the inleads together, said inleads being provided intermediate their anchored ends and their said bridge means with laterally extending approximately located in a plane transverse to the inleads and spaced from the envelope wall to impart flexibility to the said inleads.

55 4. An electric incandescent lamp comprising an envelope, a filament in said envelope, inleads anchored to and supported from the wall of said envelope and extending into the envelope from their wall anchorages in the same general direction and in spaced relation to the envelope wall

60 and connected at their inner ends to said filament, and bridge means insulatively and rigidly tying the inner end portions of the inleads together, said inleads being provided intermediate their anchored ends and their said bridge means with laterally extending approximately located in a plane transverse to the inleads and spaced from the envelope wall to impart flexibility to the said inleads.

65 5. An electric incandescent lamp comprising an envelope, a filament in said envelope, inleads anchored to and supported from the wall of said envelope and extending into the envelope from their wall anchorages in the same general direction and in spaced relation to the envelope wall

70 and connected at their inner ends to said filament, and bridge means insulatively and rigidly tying the inner end portions of the inleads together, said inleads being provided intermediate their anchored ends and their said bridge means with laterally extending opposed arcuate portions of approximately semicircular shape approximately located in a common plane transverse to the inleads and spaced from the envelope wall to impart flexibility to the said inleads.
